UNITED STATES PATENT OFFICE.

SAMUEL BERTRAM SHELDON, OF DULUTH, MINNESOTA.

METHOD OF OPERATING BLAST FURNACES.

Application filed October 11, 1923. Serial No. 668,000.

To all whom it may concern:

Be it known that I, SAMUEL B. SHELDON, a citizen of the United States, residing at Duluth, in the county of St. Louis and State 5 of Minnesota, have invented certain new and useful Improvements in Methods of Operating Blast Furnaces, of which the following is a specification.

This invention relates to a new and improved method of operating blast furnaces and more specifically to a method of applying the air blast to such furnaces.

The blast furnace now in general use is provided with a plurality of tuyères, usually 10 or 12, which are connected by bootlegs to a bustle pipe. According to common practice, the air is introduced through all of the tuyères simultaneously. From consideration of Bernouili's law of the flow of gases, 15 it is manifest that the tuyères more remote from the point where the main air line joins the bustle pipe can never pass air into the furnace with the same velocity as tuyères nearer the point of ingress of the air.

20 Further, it is found in actual practice that although the same amount and pressure of air may be supplied to tuyères continuously, the resultant pressure in the tuyère will differ from time to time. This is believed to 25 be due to what is called in practice "blast wandering" in the furnace. A large portion of the blast follows a certain upward path through the furnace because at that particular time it is the path of least resistance.

30 This will continue until some other path of lesser resistance is established. It is well known among furnace operators that during 35 only relatively short periods of time is the entire cross-section of the hearth performing for uniform melting. This blast wandering and lack of uniformity induces slips, hangs and all the various detrimental phenomena encountered in blast furnace operation.

40 If it were possible to cause the point or points of ingress of the air into the furnace to be held stationary while the furnace itself revolved, then every point in the circumference of the hearth would be subjected to 45 the same conditions, in so far as air blasting and consequent combustion is concerned. Due to structural difficulties inherent in present blast furnaces, such a course is obviously impractical. Substantially the same result can be obtained, however, by maintain-

ing the furnace stationary according to present practice and by, in effect, revolving the zone in which the air is admitted. To accomplish this result, a predetermined portion of the tuyères will be partially closed off so that air is admitted through them at relatively low pressure while the remainder of the tuyères are supplying air at full pressure. However, the particular tuyères which are supplying air under full pressure will change continuously throughout the process, additional tuyères being fully opened and others partially closed off so that the zone of full pressure air introduction travels progressively around the furnace.

50 It is an object of the present invention to provide a method of blast furnace operation whereby blast air will be supplied substantially uniformly to the different portions of the circumference of the furnace.

55 It is an additional object to provide a method of this character in which air under full pressure is supplied to a portion only of the circumference of the furnace at a time, the portion continuously changing throughout the process.

60 It is an additional object to provide a method of this character in which the zone of air blast, in effect, revolves about the furnace during operation.

65 Other and further objects will appear as the description proceeds.

I have illustrated in the accompanying drawings portions of a blast furnace adapted to permit the use of my invention there- 70 with.

In the drawings—

75 Figure 1 is a vertical section through the lower portion of a blast furnace; and

Figure 2 is a somewhat diagrammatic plan view taken approximately on the line of tuyères of Figure 1.

80 Referring now to the drawings, the furnace 3 is provided with the bustle pipe 4 from which the bootlegs 5 lead to the 100 tuyères 6. The air main 7 leads into the bustle pipe 6 as shown in Figure 2. The bootlegs 5 are each provided with the valve 8 adapted to selectively close off the bootlegs. As shown in Figure 2, the furnace 105 selected for the purpose of illustration is provided with twelve tuyères 6 which for the purpose of discussion have been lettered A to L.

85 It will be clear that when the air is intro- 110

- duced into the bustle pipe or main 7, if all the valves in the bootlegs are open, a greater quantity of air will pass through tuyères F and G than through tuyères A and L which latter are most distant from the point of introduction of the air. Consequently there will be a permanent variation of the blast in the furnace. If the valves controlling tuyères G to L are shut off, all air will enter through tuyères A to F and the amount entering through each tuyère will be increased. If the valves controlling tuyères G and L are not entirely shut off but are nearly closed so as to admit merely enough air to prevent slag forming in their nozzles, the effect upon the introduction of air through tuyères A to F is substantially the same as if tuyères G and L were entirely cut out.
- If after a predetermined period of time, the valve controlling tuyère F is nearly closed and that controlling tuyère A is fully opened, and after a further similar lapse of time the valve controlling tuyère E is nearly closed and that controlling tuyère K fully opened, and this process is continued the air blast will, in effect, revolve around the periphery of the hearth. The blast will cover the entire circumference, not simultaneously but at regular intervals. All parts of the furnace will be subjected to the same regular irregularity and the effect will be substantially the same as if the points of introduction of the air remained stationary while the furnace revolved.
- By controlling the air blast in this manner the production of channels causing blast wandering in the furnace will be minimized since the point of introduction of the air will be consequently changing. This will result in a more uniform operation and will reduce slips, hangs and other detrimental phenomena encountered in blast furnace operation.

I claim:

1. The method of blast furnace operation comprising the application of blast air under full working pressure through a portion only of the periphery, the portion changing throughout the process. 45
2. The method of blast furnace operation comprising the application of blast air under full working pressure through a portion only of the periphery, the portion changing throughout the process, and admitting air under lesser pressure through the remainder 55 of the periphery. 50
3. The method of blast furnace operation comprising the application of blast air under full working pressure through a portion only of the periphery, the portion changing 60 its location throughout the process, but remaining substantially constant in amount. 65
4. The method of blast furnace operation comprising the application of blast air under full working pressure through a portion only of the periphery, the portion progressing around the furnace during the process. 70
5. The method of blast furnace operation comprising the application of blast air under full working pressure through a portion only of the periphery, the portion progressing around the furnace during the process, and admitting air under lesser pressure through the remainder of the periphery. 75
6. The method of blast furnace operation comprising the application of blast air under full working pressure through a portion only of the tuyères, said portion consisting of a plurality of adjacent tuyères and progressing around the periphery of the furnace 80 during the operation thereof and admitting air under lesser pressure through the remainder of the periphery. 85

Signed at Duluth, Minnesota, this 1st day of October, 1923.

SAMUEL BERTRAM SHELDON.
